(57) CLAIM

The ornamental design for a pick-up bed cover, as shown and described.

DESCRIPTION

FIG. 1 is a front perspective view of a cover for the bed of a pick-up truck or similar vehicle showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is another perspective view thereof, with the cover shown open.

The pick-up truck shown in broken lines is for illustrative purposes only and forms no part of the claimed design.
